ROTARY COMPRESSOR

Harry M. Badger, New Britain, Conn., assignor to
 Landers, Frary & Clark, New Britain, Conn., a
 corporation of Connecticut

Application August 12, 1933, Serial No. 684,833

3 Claims. (Cl. 230—207)

This invention relates to rotary pumps or compressors of the type having a generally cylindrical casing within which is eccentrically mounted a revolving piston or roll of lesser diameter than the cylinder wall, the crescent-shaped space between the cylinder and piston being divided, upon each revolution of the eccentric, into a suction compartment and a compression compartment by a partition which may be in the form of a blade. My improved pump is especially adapted for use as a compressor in refrigerating apparatus, but it is not specifically limited to that use.

A general aim of the invention is to provide an improved and simplified arrangement whereby the surfaces between the relatively moving parts of the compressor are maintained in proper lubricated condition, and an effective fluid seal is provided between the suction and compression compartments within the cylinder.

More particularly, an aim of the invention is to provide in a rotary compressor of the character described an improved and simplified means whereby a lubricant, in regulated and predetermined amounts, is supplied between the piston and the cylinder wall in order to prevent wear between the parts and to provide an effective seal against the medium within the compression compartment flowing back into the inlet or suction compartment during the operation of the pump.

A further aim of the invention is to provide a rotary compressor with an improved arrangement for not only supplying a lubricant to the piston and cylinder walls, but also for maintaining the various bearing surfaces between the parts of the compressor in properly lubricated condition, the lubrication being effected by the essential parts of the compressor necessary for the primary pumping operation and without the use of any additional moving parts or instrumentalities in the way of auxiliary pumping devices, valves, unloading devices, et cetera.

A further aim of the invention is to provide in a rotary compressor an improved lubricating system having the above and other advantages and which is particularly characterized by its extreme simplicity in arrangement, the cheapness with which it may be incorporated in a compressor, and by its efficiency and reliability in operation.

Other objects will be in part obvious, and in part pointed out more in detail hereinafter.

The invention accordingly consists in the features of construction, combination of elements and arrangement of parts which will be exemplified in the construction hereinafter set forth and

the scope of the application of which will be indicated in the appended claims.

In the accompanying drawings, wherein I have shown, for illustrative purposes, one embodiment which the present invention may take,

Fig. 1 is a certain vertical section through my improved arrangement, this view being taken substantially on line 1—1 of Fig. 2;

Fig. 2 is a transverse sectional view taken substantially on line 2—2 of Fig. 1;

Fig. 3 is a longitudinal sectional view through the compressor, the same being taken substantially on line 3—3 of Fig. 2;

Fig. 4 is a transverse sectional view through the compressor, this view being taken substantially on line 4—4 of Fig. 3;

Fig. 5 is a detail view of the discharge valve; and

Fig. 6 is a view similar to Fig. 4 but showing the rotary piston in its second quarter position.

Referring to the drawings in detail, A denotes generally an oil case having a body portion 10 and a cap or head portion 12, the casing being divided by a compressor B into a low pressure chamber 13 and a high pressure chamber 14. The low pressure side of the oil case has an inlet 15 which may be suitably connected to a pipe leading from the refrigerating coil of a refrigerating apparatus, for example. The high pressure side of the oil case has an outlet 16 to which may be connected a pipe leading, for example, to the condensing means of the refrigerating apparatus. Other parts of the refrigerating apparatus aside from the compressor unit are not illustrated, as they form no part of the present invention.

The compressor B includes a casing comprising a body member or cylinder 17 to the opposite ends of which are secured plates 18 and 19 respectively provided with centrally disposed and aligned bearing sleeves or bushings 21 and 22 in which the eccentric shaft 23 is journaled. This eccentric shaft, as usual, has an eccentric portion 24 on which is mounted for relatively rotary movement a generally cylindrical piston 25 of lesser diameter than the bore of the cylinder 17. The piston is substantially tangentially arranged with respect to the cylinder wall, and this point of tangency progresses about the cylinder wall when the eccentric is turned, there being opposed to the point of tangency a crescent-shaped space. The compressor is provided with an inlet port 26 which communicates at its outer or upper end with the upper portion of the low pressure chamber 13 of the oil case. The compressor also has, closely adjacent to the inlet 26 but angularly

the bottom of the notch 34 behind the blade 31, and during the remaining portion the port will be blanked by the piston. The passage 50 is formed, in part, by a pipe 50' the lower end of which extends down into the body of lubricant in the lower portion of the chamber 13. The eccentric shaft has a longitudinally extending bore or hole 52 which is parallel to, but offset slightly from, the axis of the shaft in order to balance the shaft. The longitudinally extending bore 52 is 10

ton. This pocket will hold a drop or two of oil.

With the lubricating arrangement described, it will be understood from the foregoing description that, while the piston is moving away from the blade, oil will be sucked from the reservoir in the lower portion of the low pressure chamber into the notch 34 behind the blade, and during this time the eccentric blanks the outlet duct 55. As the piston moves towards the blade, that is, during the second half of the complete stroke of the piston, the channel 54 is in registry with the outlet duct and the oil is forced or pumped into the bore or hole 52 in the eccentric and thence to the bearing surfaces, as previously described. Some of the oil will be thrown by centrifugal force into the pocket 59 which is blanked by the shoulder 61, except when this pocket comes into registry with the inner end of the duct 62. The pocket and duct are so arranged that they register on the suction portion of the stroke of the rotary piston and at a time when the outlet duct 55 is blanked so that the force of the oil pump comprising the blade and notch is not effective in forcing the oil through the duct 62. When the pocket 59 registers with the inner end of the duct 62, there is a suction within the intake compartment 29 so that the oil within the pocket will be sucked out of the pocket through the duct 62 and into the inlet port 26 where it will become thoroughly co-mingled with the incoming refrigerant or other medium. The oil will, of course, spread over the periphery of the rotary piston and flow down the contacting surfaces on the ends of the piston and the end plates 18 and 19. The lubricant forms a seal between the wall of the cylinder and the rotary piston at a point at which these members are substantially in tangency and prevents the compressed medium in the compression compartment from flowing back into the intake compartment. The oil admitted to the intake compartment will be carried by the compressed lubricant through the discharge valve and it will then be carried through the system back to the low compression chamber 13. It is of importance to note that the lubricant is supplied to the rotor at the desired rate of feed and in the exactly required amounts, a predetermined amount being sucked into the compartment chamber with the incoming medium on each rotation of the piston. The size of the pocket 59 determines the amount of lubricant admitted to the crescent-shaped space between the piston and the cylinder. The oil to the bearings and the crescent-shaped space is supplied from the low compression side of the apparatus so that overloading of the pump with oil or the accumulation of oil within the pump when the pump is at rest, is entirely obviated, and thus the necessity of providing separate or additional means for removing oil from the pump when it is desired to start the pump is entirely obviated. Lubrication of the several parts is effectively maintained without adding any additional moving parts to the apparatus or materially adding to the cost thereof.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

It is also to be understood that the language used in the following claims is intended to cover

all of the generic and specific features of the invention herein described and all statements of the scope of the invention which, as a matter of language, might be said to fall therebetween.

I claim as my invention:

1. In combination, an oil case, a compressor located therein and dividing said case into a low pressure chamber and a high pressure chamber, said compressor having a casing provided with a cylinder having an inlet communicating with the low pressure chamber and an outlet communicating with the high pressure chamber, a piston eccentrically mounted in and of smaller diameter than said cylinder and having a notch in its periphery, a shaft for eccentrically moving said piston in said cylinder, a partition member slidably engaging in said notch and dividing the space between said cylinder and piston into an intake compartment and a compression compartment; said shaft having a radially disposed bearing surface, an oil hole, and a pocket in said bearing surface in communication with said oil hole; said casing having a thrust bearing surface with which said shaft mentioned bearing surface cooperates, a spring urging said shaft in a direction to resiliently hold said bearing surfaces against one another, a duct leading from the bearing surface of said casing to said intake compartment, said pocket being adapted to register with said duct on each revolution of the shaft, an oil inlet port leading from the low pressure chamber and adapted to admit a lubricant therefrom into said notch as the space therein behind said partition member increases, and means for permitting discharge of lubricant from said notch to said oil hole as the space within said notch decreases, said shaft being arranged to prevent communication between said oil hole and notch when said pocket is in registry with said duct which leads to said intake compartment.

2. A rotary pump including a cylinder, a piston eccentrically mounted in and of smaller diameter than said cylinder, there being a crescent shaped space between said elements, a shaft for eccentrically moving said piston relative to said cylinder to progress said space, a partition member dividing said space into an intake compartment and a compression compartment, a thrust bearing surface on said cylinder, a radially extending bearing surface on said shaft engaging said thrust bearing surface, a spring carried by said shaft and urging the same endwise whereby said bearing surfaces are resiliently held in engagement, said bearing surface of said shaft having a pocket adapted to contain a predetermined amount of lubricant, a duct leading from said thrust bearing surface directly to said intake compartment, said duct and pocket being constructed and arranged to register on each rotation of said shaft and on the suction portion of the stroke of said piston, said duct being closed by said bearing surface on said shaft at all times except when said pocket and duct are in registry, and means for supplying lubricant to said pocket.

3. A rotary pump including a cylinder, a piston eccentrically mounted in and of smaller diameter than said cylinder, there being a crescent shaped space between said elements, a shaft for eccentrically moving said piston relative to said cylinder to progress said space, a partition member dividing said space into an intake compartment and a compression compartment, said cylinder having a thrust bearing surface and said shaft having a radially extending bearing surface en-

gaging said thrust bearing surface, a spring urging said shaft endwise to hold said bearing surfaces in frictional engagement; said shaft having an oil hole therein; a pocket in said 5 radially extending bearing surface adapted to hold a predetermined amount of lubricant, and a duct leading from said oil hole to said pocket; a duct leading from said thrust bearing surface directly to said intake compartment and adapted 10 to register with said pocket on each rotation of

the shaft and while said last mentioned duct is under the influence of the suction action within said intake compartment and said last mentioned duct being closed by said bearing surface on said shaft at all times except when said pocket registers therewith, and means for delivering lubricant to said oil hole only when said pocket and last mentioned duct are out of registry. 5

HARRY M. BADGER. 10
